Patented Dec. 21, 1926.

UNITED STATES PATENT OFFICE.

ARTHUR J. PRATT, OF CAMBRIDGE, MASSACHUSETTS, ASSIGNOR TO AMERICAN OPTICAL COMPANY, OF SOUTHBRIDGE, MASSACHUSETTS, A VOLUNTARY ASSOCIATION OF MASSACHUSETTS.

PROCESS FOR FINISHING SEAMS OF LEATHER GOODS.

Application filed August 4, 1925. Serial No. 48,177.

This invention relates to a new and useful process for finishing the seams of leather goods, and has particular reference to the finishing of eyeglass and spectacle cases.

5 Prior to the present invention it has been customary in the manufacture of cases of the character stated, to finish the seams thereof either by burnishing the same by hand with an ordinary hand tool, or by 10 means of a revolving burnishing wheel. Both of these methods, however, necessitate the unnecessary expenditure of considerable time and labor, with the result that the cost of manufacturing these cases is somewhat 15 increased.

It is, therefore, one of the principal objects of the present invention to produce a process for finishing or burnishing the seams of eyeglass and spectacle cases which will 20 cheapen the cost of manufacture of the same, and which will overcome all of the other disadvantages encountered in the use of these former methods.

Another object is to provide a process 25 which consists of a minimum number of operations, all of which are extremely simple and easily performed.

Other objects and advantages of the present improved process will become more readily 30 apparent from the following description when taken in connection with the accompanying drawing, wherein has been disclosed one way in which the method may be performed.

35 In the drawings, forming a part of this application:

Figure 1 is a perspective view of a finished case;

Figure 2 is a view of a portion of a case 40 showing the seam before it is finished;

Figure 3 is a sectional view showing one way that may be employed for carrying out my method, and showing the seam before it has been finished;

45 Figure 4 is a similar view showing the seam after the finishing operation.

As an example of my improved mode of procedure, I first take a case, the seams of which have been stitched but have not been finished, and then place the case over a supporting die or anvil. I next clamp the unfinished seam between suitable clamping members, and then bring into contact therewith a heated plunger, which presses the

seam and burnishes the same, whereby to 55 form a finished surface.

It is customary to form cases of the type herein described and illustrated from a single length of material which is folded to provide front and rear sides and a cover 60 portion, after which the adjacent ends of the two sides are stitched together and the rough seams subsequently finished.

Referring particularly to Figure 1, I have disclosed a finished case, which comprises 65 front and rear sides 10 and 11, respectively, the rear side 11 of which is formed with an extension flap, which overlaps the front side 10 to form a cover portion 12. After the material has been folded the adjacent 70 end portions of the sides thereof are secured together by means of the stitching 13.

By referring to Figure 2 it will be seen that the stitching is disposed slightly inwardly from the end edge of the case, which 75 leaves a very rough seam, and it is then necessary to burnish this seam to form a finished surface.

In Figures 3 and 4, I have shown one example whereby my improved method may 80 be accomplished, and certain apparatus which may be used in conjunction therewith. This apparatus consists of a supporting die or anvil 14, a pair of suitable clamping members 15, and a heated plunger 16, which plunger is formed with a reduced end 17 85 having a groove 18 in the bottom face thereof, the approximate curvature of which is arranged to be imparted to the finished 90 seam.

After the ends of the sides of the case have been stitched together, the said case is placed over the supporting die or anvil 14, as shown in Figures 3 and 4, and the unfinished ends of the sides are then firmly 95 clamped and held between the suitable clamping members 15. While held in this position the heated plunger 16 is lowered and the reduced end 17 thereof passing downwardly between the clamping members 15, engaging with the unfinished end edge of the case, presses the same, as shown in Figure 4, whereby to form a finished 100 seam or surface. The curve of the finished surface will be approximately equal to the curvature of the groove 18 in the bottom of the plunger.

It will be clearly understood that as the

plunger is lowered it crushes the outer edges of the seam simultaneously throughout the length of the seam to a smooth and burnished surface.

5 From the above it will be readily appreciated that I have provided a very simplified process, consisting of a minimum number of operations, and that while I have referred to the same as being particularly used in connection with spectacle or eyeglass cases, it will, of course, be understood that it may be employed for finishing the seams of leather goods of any character to which it may be applicable.

10 15 Having thus described my invention, I claim:

1. The process of making a smooth burnished seam on two pieces of leather held

together, comprising securing two pieces of leather together face to face, holding the 20 seam portion securely, and pressing the entire length of the outer edges of the seam simultaneously to a smooth burnished surface.

2. The process of making a smooth burnished seam on a plurality of pieces of leather held together, comprising crushing down the outer edges of the seam simultaneously throughout the length of the seam to a smooth surface. 25

3. The process of making a smooth burnished surface on the edge of a piece of leather, comprising crushing down the outer edge of the piece of leather simultaneously throughout its length to a smooth surface. 30

ARTHUR J. PRATT.
